MICROTOME

Josef Blum, Norwalk, Conn., assignor to Ivan Sorvall, Inc., Norwalk, Conn., a corporation of New York

Application April 8, 1955, Serial No. 500,110

39 Claims. (Cl. 88—40)

This invention relates to microtomy and more particularly to an improved machine for producing ultra thin sections of tissues for both optical and electron microscopy.

The purpose of the present invention is to provide an improved microtome instrument that is rugged, easy to operate, practically maintenance free, and which is capable of producing ultra thin sections of biological tissues in order of from $\frac{1}{40}$ to $\frac{1}{2}$ micron of exceptional quality and uniformity.

The instrument of the present invention embodies an extremely reliable and accurate means for advancing the specimen to the knife; a collet type chuck which is adapted to hold the specimen firmly at any desired angle and to provide facility for rotating or changing the specimen; and a knife holder mounting stage which provides for fine and coarse adjustment of the stage relative to the specimen.

A salient feature of the present invention is the novel means for passing the specimen against the knife in only one direction and providing a return stroke for the specimen that bypasses the knife, thereby minimizing static friction and eliminating damage to the specimen.

A further feature of the microtome of the present invention is the provision of compensating spring suspensions for all the moving mechanical components which precludes readjustment of parts under normal conditions so as to render the instrument practically maintenance free throughout its long life.

There are also provided a number of spherical balls for use in critical pivoting locations so as to provide high precision support for the moving members which are articulated, retracted or indexed with the minimum amount of pressure.

A novel adjustable knife holder is also provided which is adaptable for versatile adjustment and which permits lateral movement of the knife without any change of preset angle.

An important feature of the knife holder is the provision of a three point mounting structure which permits the utilization of an irregular or broken piece of glass as a knife.

Means are also provided in the instrument of the present invention to automatically retract the control pawls from gear teeth on return strokes of the advancing mechanism, thereby preventing chattering and eliminating vibrations that might otherwise introduce errors in the functioning of the machine.

Another novel feature of the present invention is the provision of simple means for resetting the advancing mechanism without disassociating any of the parts in such a way as to require subsequent re-adjustment.

Still other objects and advantages of the invention will be apparent from the specification.

The features of novelty which are believed to be characteristic of the invention are set forth herein and will best be understood, both as to their fundamental principles

2

ples and as to their particular embodiments, by reference to the specification and accompanying drawings, in which:

Figure 1 is a side and rear perspective view of the microtome of the present invention;

5 Fig. 2 is a perspective view of the opposite side of the instrument shown in Fig. 1;

Fig. 3 is an enlarged side view, partly in cross section and partly in phantom outline, some parts being omitted, of that front portion of the machine constituting the

10 knife holder, the knife holder stage, the specimen holder, and the means for moving the specimen relative to the knife;

Fig. 4 is an enlarged view, partly broken away, partly in section, taken on the line 4—4 of Fig. 5, and partly in phantom outline, of the rear portion of the microtome showing the mounting for the rear portion of the specimen arm and the advancing mechanism for the arm;

Fig. 5 is a side view taken on line 5—5 of Fig. 4;

20 Fig. 5A is a schematic representation of a portion of the advancing mechanism in one position;

Fig. 5B is a schematic representation of said advancing mechanism in a second position;

Fig. 6 is a greatly enlarged side view taken along line 6—6 of Fig. 4, partly in section, partly in elevation and partly in phantom outline;

Fig. 7 is a top view taken along line 7—7 of Fig. 6;

Fig. 8 is a view, partly in section, taken along line 8—8 of Fig. 3;

25 Fig. 9 is a fragmentary enlarged view, partly in section, taken along line 9—9 of Fig. 8;

Fig. 10 is a view taken along line 10—10 of Fig. 3;

Fig. 11 is an exploded view, partly in section of the knife holder shown in Fig. 8;

30 Fig. 12 is an enlarged side view, partly in section, of the mounting means for the cutting knife;

Fig. 13 is a view, partly in section and partly in phantom outline, taken along line 13—13 of Fig. 3;

Fig. 14 is an enlarged bottom view of a mid-portion of the base casting of the instrument showing the casting structure as well as a bottom view of a portion of the advancing mechanism; and

40 Figs. 15 through 20 are a series of enlarged views of the pawl, ratchet and cam elements which form part of the advancing mechanism, several of these figures being partly broken away and partly in phantom outline.

45 Referring now to the drawings in detail, the microtome of the present invention is mounted on a base generally designated 31, made of a casting of light weight but strong metal such as aluminum, aluminum alloy or the like. In one embodiment the casting of base 31 comprises four substantially parallel vertically extending longitudinal walls 32, 33, 34 and 35 (Fig. 14), which are joined to each other by end walls 36 (Fig. 1) and 37 (Fig. 3). The structure of the base is reinforced by partitions 38 which extend laterally at various strategic positions between respectively adjacent walls 32, 33, 34 and 35.

50 In a preferred embodiment, the longitudinal walls, the end walls and partitions are formed in one integral casting to provide a light but rigid support for the microtome.

55 There is also provided a pair of platform rails 41 and 42, rail 41 being cast integrally on the tops of walls 32 and 33 and coextensive therewith, rail 42 being cast integrally with the tops of walls 34 and 35 and coextensive therewith. The top surfaces of rails 41 and 42 are lapped flat and accommodate the superstructure of the machine.

60 Base 31 may optionally be provided with ears 43 at the lower edges of walls 32 and 35 with suitable vertical apertures 44 for the insertion of bolts for rigidly mounting the machine on a suitable table or platform. (Figs. 1 and 2.) In other embodiments, the base may be supported by stiff or resilient pads 45 made of rubber, neo-

prene, felt, or the like, as shown in Fig. 8. Mounted on rails 41 and 42 is a support frame, generally designated 51, having side walls 52 and 53, respectively, rear wall 54 and a floor 55 secured to rails 41 and 42 by suitable means, such as bolts, or the like, not shown. 5 (Figs. 1, 2 and 4.)

The top of frame 51 has a pair of forwardly extending substantially parallel arms 58 and 59 (Figs. 1 and 5) which form the support means for the compound pivoting assembly to be described hereinbelow. Near the forward end of shoulder 58 there is a vertical lateral slot 61 (Fig. 2), the lower end of which terminates in a collar 62 which encircles horizontal pin 63. (Figs. 2 and 4.) Pin 63 is secured within collar 62 by means of horizontal screw 64 threadably extending across slot 61. The inner vertical surface of support pin 63 has a bearing recess for seating pivot ball 65.

The outside vertical surface of shoulder 59 has a horizontal elongated recess 71 (Figs. 1 and 5) within which a flat leaf spring 72 lies, the rear portion of the spring being secured to the vertical wall of the recess by means of screws 73.

The forward end of shoulder 59 has a horizontal transverse clearance hole 74 (Fig. 4) over which the forward end of leaf spring 72 extends. The forward end of leaf spring 72 has a bearing recess for seating pivot ball 76. In some embodiments the recess may alternatively be substituted by a pierced hole provided its diameter is smaller than that of ball 76.

The mechanism for advancing the specimen block towards the microtome knife is mounted pivotally between balls 65 and 76. (Fig. 4.) The advancing mechanism comprises a U-shaped yoke, generally designated 80, having upwardly extending arms 81 and 82. Arm 81 has a horizontal socket rod 83 secured therein, the outer end of said rod having a bearing recess which accommodates ball 65. Arm 82, on the other hand, has a horizontal socket rod 85 mounted fast therein and extending into aperture 74 and rotatable freely therein. A bearing recess 86 on the outer vertical wall of socket rod 85 is adapted to accommodate ball 76. Yoke 80 is freely pivotable between shoulders 58 and 59 on spherical balls 65 and 76, the loading on the suspension being provided by the tension on the forward free end of leaf spring 72. Yoke 80 has a downwardly extending lever leg 87 whose function will be described hereinbelow.

Positioned between the upwardly extending arms 82, 83, of yoke 80, is an arm support pivot block 91 in the form of a rectangular casting having a generally rectangular central aperture 92. Mounted on each vertical outward surface of pivot block 91 is a leaf spring 93 having a central bow 94 that bulges outward and is spaced apart from its respective vertical wall of the pivot block. In the intermediate portion of each bow 94 is a bearing recess or aperture adapted to seat balls 95 and 96, respectively, which are also seated in respective recesses 97 and 98 in the inner vertical faces of socket rod 83 and socket rod 85, respectively.

Bows 94 of springs 93 normally urge outwardly against balls 95 and 96 and provide a preloaded tension therefore, thereby eliminating back lash or lost motion in the pivoting action of pivot block 91 relative to yoke 80. The horizontal axes of balls 65 and 76 are aligned with each other, the common axis line being spaced slightly apart vertically from the common horizontal axis line of balls 95 and 96. This is graphically illustrated in Fig. 5A which shows generally the relative positions of balls 76 and 96. As the bottom of yoke 80 moves forward it pivots on balls 65 and 76, whereby balls 95 and 96 are carried forward to a predetermined fractional extent of the movement of yoke 80. Since pivot block 91 is suspended between balls 95 and 96, its movement is coextensive with that of the balls. The purpose of this compound pivoting mechanism will be elucidated hereinbelow.

Each of the respective upper and lower horizontal bars

of pivot block 91 has a vertical central aperture. The two apertures are axially aligned with each other and accommodate a pivot pin 101 rotatable therein on its longitudinal axis. The top and bottom faces of pin 101 are exposed through the respective apertures and have bearing recesses 102 and 103 which accommodate balls 104 and 105, respectively. Balls 104 and 105 are seated in suitable bearing recesses in the central portions of leaf springs 106 and 107, respectively, mounted on the top and bottom faces respectively of pivot block 91. Leaf springs 106 and 107 each have a pair of lateral ridges 108 formed on each side of the ball seating location whereby the central bowed section of said springs are adapted to preload balls 104 and 105 in order to prevent lost motion in the rotation of pivot pin 101 and to prevent back lash thereof.

Mounted fast upon pivot pin 101 is horizontal specimen advancing bar 111 which is adapted to swing in a horizontal plane relative to pivot block 91 within certain limits. Bar 111 extends to the forward parts of the machine and at its end there is mounted the specimen holder which will be described hereinbelow.

In order to advance the specimen at the forward end of bar 111 toward a cutting knife, the requisite motion is imparted by the motion of pivot block 91 whose suspension points—balls 95 and 96—are displaced by the pivoting action of yoke 80. See Figs. 5A and 5B. Advancing bar 111 is also capable of independent vertical pivoting motion on balls 95 and 96, independently of the motion of the pair of balls 95, 96 relative to the pair of balls 65 and 76. Hence, the three sets of pivots described provide for forward, backward, horizontal, and vertical motions of the forward end of the bar, and accordingly, the corresponding motions of the specimen as well.

Mounted on the rear end of bar 111 is a stud 112 whose outer end is engaged by one end of a downwardly extending spring 113 whose other end is anchored on horizontal stud 114, mounted in rear wall 54 of frame 51. (Fig. 5.) One purpose of spring 113 is to pull down upon the rear end of bar 111 in order to eliminate back lash in the motion of the bar. A more detailed description of this action will be provided hereinbelow.

There will now be described the means for moving the specimen at even increments toward the cutting knife:

Downwardly extending lever leg 87 of yoke 80 which moves freely within a longitudinal slot in floor 55, is arranged to engage a mechanism by which it is moved in a forward direction. As shown in Figs. 5, 6, 7 and 14, the advancing mechanism comprises a horizontal rotatable screw 120, having a plurality of buttress saw-tooth threads 121, and supported at its axial points by means of balls 122 and 123 that are seated in bearing recesses 124 and 125, respectively, in the opposite ends of said screw. Rear ball 122 is seated in bearing recess 126 on stud 127 connected to bracket 128 which is attached to the lower edge of wall 54 of frame 51 and which extends downward into aperture 129 in wall 36 of base 31. (Fig. 1.) Ball 123 at the forward end of said screw is seated in a bearing recess in vertical leaf spring 131 whose upper end is connected rigidly between anchor block 132 attached to a forward portion of the floor 55 of frame 51.

Spring 131 has adequate strength and is biased with sufficient tension toward the rear of the machine to provide a secure mounting for screw 120 between balls 122 and 123. Spring 131 also has sufficient resilience to provide for temperature compensation by accommodating the expansion or contraction of screw 120 as well as to provide an anti-backlash seating for the screw, and to prevent any lost motion that might otherwise be incurred as in previous mechanical arrangements.

Pivotedly mounted on the lower end of lever leg 87 of yoke 80 is an H-yoke generally designated 135, having a cross bar 136, a pair of rearwardly extending legs 137

and a pair of forwardly extending arms 138. See Figs. 5, 6, 7 and 14. Legs 137 engage the respective ends of pivot pin 139 extending transversely through leg 87. Yoke 135 extends forwardly and generally horizontally from leg 87, a portion of the bottom of leg 87 being recessed at 140 to permit the vertical motion of said yoke.

Threadably secured into cross bar 136 is a pin 141 which extends forwardly between arms 138 of yoke 135 and terminates in ball 142, to the top of which is connected a pair of forwardly extending clamping springs 143, the ends of which curve downward and rearwardly. To the ends of springs 143 is mounted rider block 144 which extends rearwardly into the area below the space between arms 138 of yoke 135, said block being urged upwardly by said springs against ball 142. The top of rider block 144 has a channel 145 within which pin 141 is accommodated. The bottom of block 144 is serrated in the form of buttress saw teeth that mate precisely with threads 121 on screw 120.

It will be noted that by virtue of the spring mounting of block 144 and of the width of channel 145, said block is capable of a limited swivelling action, while at the same time it is prevented from moving longitudinally relative to yoke 135. Thus, the block is provided with freedom to accommodate itself to threads 121 on screw 120 without causing any longitudinal motion on the part of the lower end of leg 84 relative to said screw, thereby preserving the accuracy of the specimen advancing mechanism.

Rider block 144 is urged downward upon threads 121 by means of vertical pressure pin 147 mounted slidably in vertical slot 148 in leg 87. A captive spring 149 (Fig. 4) within slot 148, causes the lower end of pin 147, extending through recess 140, to bear downward upon cross bar 136 of H-yoke 135, maintaining the teeth of block 144 in intimate engagement with the threads 121 on screw 120. Thus, the rotation of screw 120 causes rider block 144 to move forward or backward depending upon the direction of rotation of the screw whereby leg 87 of yoke 80 is caused to move forward or backward as desired.

The lower part of yoke 80 is normally urged rearwardly by means of spring 151 (Fig. 5), one end of which is connected to hook 152 mounted in the rear surface of yoke 80, the other end of which is connected to hook 153 mounted on the forward surface of wall 54 of frame 51. The action of spring 151 also urges rider block 135 rearwardly and enhances the engagement of its teeth with threads 121 on screw 120, thereby eliminating backlash or lost motion on the part of the screw action.

While the teeth of rider block 144 are in engagement with the threads of lead screw 120, spring 151 is prevented from urging the lower end of yoke 80 backwards towards frame 54. When, however, it is desired rapidly to retract the lower end of the yoke backward in order to start a new cutting cycle, rider block 144 may be lifted from screw threads 121 by means of forwardly extending curved slide rod 155 that is mounted pivotally on bracket 128 by means of screw 156.

As shown in Figs. 6 and 7, slide rod 155 is operated by arm 157 of bell crank 158 whose pivot pin 159 extends through walls 32 and 33 of base 31. The outer end of pivot pin 159 has a handle 160 which can be manipulated manually to move inner arm 157 upwardly thereby moving rod 155 upwardly to bear against pin 161 extending outwardly from one of the forward arms 138 of H-yoke. When rod 155 bears upwardly against pin 161, H-yoke 135 is lifted free from threads 121 against the action of pressure pin 147, thereby pivoting H-yoke upwards and permitting spring 151 to draw the lower end of yoke 80 pivotally toward the back of the machine. Thus, the operator may automatically reset the advancing mechanism back to its starting position by merely de-

pressing handle 160 on the outside of the machine (Fig. 1).

In order to prevent crank arm 157 from dropping too far, a support pin 162 mounted in and extending inwardly from wall 33 (Fig. 7) serves as a stop for crank 158 when handle 160 is released, thereby permitting rod 155 to fall by gravity and to remain supported in its inoperative position upon arm 157, as shown in Figs. 6 and 7. Rod 155 may be curved in a suitable manner in order to provide a smooth lifting action for pin 161 of yoke 135.

It has been found advantageous to provide that block 144 be made of a suitable resilient plastic material such as the one presently known as Teflon, or the like. Although such materials are resilient, they have sufficient toughness to preserve their shape, and this particularly is important when it is necessary to provide block 144 with serrations to mate evenly and repeatedly with threads 121 on screw 120. Also, such a material is advantageous in the event of accidents, for should block 144 bounce or otherwise strike against screw 120, there would be no damage either to the screw threads or to the block because of such a contingency.

In order to prevent any damage to the yoke by the action of spring 151, there is provided a stop 163 (Fig. 5) connected to the rear end of the slot in floor 55 of frame 51 by means of screw 164 whose head is recessed from the forward surface of said stop in order that it is not impinged upon by leg 87 of yoke 80. Stop 163 may be made of a suitable resilient material such as rubber or neoprene, to absorb any shock caused by the sudden backward movement and contact of leg 87 with said stop.

The spatial relationship between stop 163, the lower leg 87 of yoke 80, and rider block 144 may be so arranged that when yoke 80 has been retracted to its rearwardmost position, and rod 155 has been permitted to move downward by releasing handle 160 of bell crank 158, rider block 144 will be lowered into engagement with at least a few turns of threads 121 on lead screw 120 so that the action of moving the specimen forward may be resumed upon rotation of screw 120.

By means of a mechanism to be described hereinbelow, horizontal specimen advancing bar 111 is moved vertically upon pivot balls 95 and 96 by manually operated mechanical means to cause the specimen to pass against the cutting knife, and to bypass the knife on its return stroke. Coordinated with the movement of bar 111 is a mechanism for rotating the lead screw a predetermined amount in order to advance said bar longitudinally a predetermined distance so that the specimen will be advanced accordingly by this same predetermined distance toward the cutting knife to slice tissues of the desired thickness.

This rotating mechanism comprises a horizontal arm 171 (Figs. 1, 2, 4, and 5) whose rearward end is connected by press fit into pivot block 91 and which extends forwardly in the same general direction as bar 111 whose pivotal motion it duplicates. Pivotedly connected to arm 171 by means of pin 174 is a descending lift rod 175, the lower end of which is pivotally connected to pin 176 mounted between the lateral arms 178 of yoke 179. Yoke 179 is freely pivotable around horizontal stationary shaft 181 (Figs. 6 and 7) which is mounted fast by means of set screw 182 to downwardly extending leg 183 of block 132. With each upward and downward stroke of rod 175, yoke 179 reciprocates pivotally around shaft 181.

Mounted substantially parallel to shaft 181 and fixed fast within arms 178 of yoke 179 is bushing 184 through which shaft 185 extends, said shaft being rotatable on its longitudinal axis within said bushing. Mounted on the rear end of shaft 185 and rotatable therewith is pawl 186 which is adapted to engage teeth 187 on the periphery of ratchet wheel 188 mounted fast on screw 120 by means of set screw 189, the rotation of said ratchet wheel causing the rotation of screw 120.

7
Mounted on the forward end of shaft 185 and rotatable therewith is a second pawl 191 which coacts with the periphery of limiting disc 192. Disc 192 is fixed by suitable means, such as press fitting or otherwise, to bushing 193 that is mounted around and is rotatable relative to shaft 181, the latter shaft being positioned coaxially relative to screw 120. Limiting disc 192 has substantially the same diameter as ratchet wheel 188 except for a portion of its periphery that is recessed to form a cam surface 194. See Figs. 6, 7 and 15.

A wire 195 is coiled around bushing 184, the forward end of the wire being connected to the rearward arm 178 of yoke 179, and the rearward end of said wire being extended over the top of pawl 186 to limit the outward movement of said pawl and, accordingly, of pawl 191. Since pawls 186 and 191 are fixed fast upon shaft 185, the rotational movements of all three of said elements are integral with each other.

By observing Figs. 15 through 17, it will be noted that while both pawls 186 and 191 are mounted fast upon shaft 185 and rotate therewith, the operative points of the respective pawls are radially offset from each other by a prescribed distance. Whenever the point of pawl 191 is urged into recess 194 of limiting disc 192, the point of pawl 186 is engaged with teeth 187 of ratchet wheel 188. See especially Figs. 15 and 18. When, however, pawl 191 is rotated outwardly from cam 194 and rides on the outer periphery of limiting disc 192, shaft 185 is rotated, causing pawl 186 to rotate therewith and to disengage from teeth 187 of ratchet wheel 188, as can be seen in Fig. 16, for example.

Assuming that limiting disc 192 is in a fixed predetermined position, it will be seen that upon the vertical reciprocal motion of rod 175, moving yoke 179 pivotally around shaft 181, cam 191 will be moved inward and outward at certain predetermined times as determined by the rise portion of cam surface 194, and therefore it will control the motion of pawl 186 to cause the latter to engage and disengage the teeth 187 of ratchet wheel 188. This control by pawl 191 over pawl 186 predetermines the position at which pawl 186 will engage teeth 187 of ratchet wheel 188, and the duration of said engagement, thereby predetermining the amount of rotation that will be effected upon ratchet wheel 188, and accordingly, screw 120. The degree of rotation of screw 120 with each reciprocating cycle of lift rod 175 determines the distance by which bar 111 is advanced thereby determining the thickness of the specimen tissue that will be cut, as will be described in greater detail hereinbelow.

Fig. 18 shows a typical preselected position of limiting disc 192 whereby cam 186 will be engaged with ratchet wheel 188 for substantially the full amount of the stroke of lift rod 175. Fig. 16 shows a preselected position of disc 192 whereby cam 186 will be engaged with wheel 188 for a very minor portion of the duration of the stroke of rod 175. Any intermediate positions for disc 192 may be preselected by the operator as will be described below.

Each cycle of reciprocating action of lift rod 175 is intended to cause the alternate engagement and disengagement of pawl 186 with ratchet wheel 188, the period of said engagement causing screw 120 to rotate a predetermined radial distance for advancing the specimen to the tissue cutting knife. This action requires a reciprocating radial motion on the part of pawls 186 and 191, and this is accomplished by means of a curved friction spring 201 attached on the forward end of shaft 185 and rotating therewith. (Figs. 7, 14.)

Spring 201 extends laterally between and is frictionally engaged jointly by limiting disc 192 and a friction disc 202, the latter being attached by suitable means, such as press fit or otherwise, to bushing 193 and rotatable therewith. As can be observed from Fig. 19, when rod 175 moves upward to move arms 178 of yoke 179 upward, the frictional resistance of spring 201 between discs 192 and 202, which at the moment are stationary, will

cause shaft 185 and pawls 186 and 191 to rotate toward their respective cooperating elements, namely ratchet wheel 188 and limiting disc 192, whereby said ratchet wheel will be engaged and rotated for a distance equivalent to the distance which pawl 191 has traversed within cam recess 194 of limiting disc 192. Thus, the upward stroke of rod 175 causes the rotation of screw 120 for advancing the specimen to the tissue cutting knife.

On the downward stroke of rod 175, the frictional resistance of spring 201 between stationary discs 192 and 202 will cause shaft 185 to rotate and cause pawls 186 and 191 to rotate promptly outward from the peripheries of their respective coacting elements, namely ratchet wheel 188 and limiting disc 192. See Fig. 20. This action is also useful for rapidly disengaging pawl 186 from ratchet teeth 187 thereby preventing the pawl from bouncing on, or rubbing against, said teeth during the return stroke, which actions might otherwise introduce undesirable characteristics of wear and inaccuracy into the apparatus. 20 During the downward stroke of rod 175, screw 120 remains stationary.

During the downward stroke of rod 175, the outward movement of pawl 186 is limited by the rearwardly extending end of wire 195, and in this manner spring 201, 25 which rotates with shaft 185, is prevented from escaping from between discs 192 and 202. Obviously, on the upward stroke of rod 175, spring 201 cannot escape from between said friction discs because the inward rotational motion of pawls 186 and 191 is limited by their coacting elements.

The amount of rotation of ratchet wheels 188, and accordingly screw 120, to be caused by pawl 186 is determined by the position of limiting wheel 192 and the radial relationship of its recessed cam 194 relative to screw 120. The position of limiting cam 194 may be adjusted by means of gear wheel 205 attached fast to bushing 193, whereby said gear wheel rotates co-radially with limiting disc 192 (Figs. 4, 6 and 7).

It will be noted that gear wheel 205, friction disc 202 and limiting disc 192 all rotate co-radially with each other on bushing 193, which rotates freely around shaft 181. The longitudinal movement of bushing 193 is prevented by end collar 206 mounted fast by means of a set screw or otherwise to shaft 181.

40 45 50 55 60 65 70
The peripheral teeth of gear 205 are engaged by a worm 207 (Figs. 4, 7) attached by means of set screw 208 to shaft 209 which extends laterally and is rotatably supported in sleeve bearing 210 extending laterally through walls 32 and 33 of base 31. Mounted on the outer end of shaft 209 which extends outside of wall 32 (Figs. 1, 4 and 14) is a knurled knob 211 which may be grasped and rotated manually by the operator.

Knob 211 has a flange 212 having a graduated scale printed or etched thereon which indicates the thickness of the tissue that it is desired to cut. A plate 213 having an index line is mounted on the outer surface of wall 32 adjacent flange 212 so that the latter may be set in the desired position. As knob 211 is rotated, worm 207 rotates gear 205 thereby rotating limiting disc 192; and the latter may be set at any desired position as indicated by the graduated scale on flange 212 that has been suitably calibrated relative to the cam recess 194 and ratchet teeth 187. By this means the operator can set the instrument to cut tissues of a desired thickness by simply rotating knob 211 to the requisite indicated point on the calibrated scale of flange 212.

The means for controlling the cyclic motions of specimen advancing bar 111 relative to its compound pivots are mounted upon a vertical frame, generally designated 221, attached by bolts 222 to rails 41 and 42 intermediate the front and rear of the machine (Figs. 1, 2, 3 and 13). Frame 221 comprises a pair of vertical posts 223 and 224, to the front edges of which is connected guide plate 225 by means of bolts 226 or the like. In

some embodiments guide plate 225 may be separated from posts 223 and 224 by spacers 227, while in other embodiments it may be flush with or cast integrally with the front of posts 223 and 224.

Guide plate 225 has a central aperture 228 through which bar 111 extends, the contours of aperture 228 being designed to determine the path described by said bar as it is moved through the cutting cycle.

The means of providing mechanical motion for bar 111 comprises an operating wheel 231 having a handle 232 which is grasped manually by the operator to rotate the wheel. See Figs. 1, 2, 3 and 13. Wheel 231 is mounted upon a shaft 233 which extends rotatably through horizontal bushing 234 (Fig. 13) mounted through post 223 of frame 221. Mounted on and rotatable with the inner end of shaft 233 is a crank disc 235 secured to said shaft by means of set screw 236 in hub 237 of said disc.

Connected near the outer periphery of crank disc 235 is a stud 241 upon which is mounted laterally extending crank pin 242 to which is pivotally mounted the lower end of link 243, which is adapted to articulate loosely around said pin. Threadably inserted into the upper end of link 243 is a turnbuckle 244 whose upper end is threadably engaged by the lower end of link 245, the upper end of which is loosely articulated with a horizontal pin 246 mounted horizontally between the legs 247 of yoke 248 mounted around bar 111. The upwardly extending arms 251 form a clamp around bar 111 which may be tightened and loosened by means of shoulder screw 252 extending freely through one of the arms and threadably engaging the other arm.

By rotating turnbuckle 244 it is possible to adjust the overall length of the linkage between crank wheel 235 and bar 111. The articulating connections at the ends of said linkage permit not only vertical motion, but horizontal motion as well, on the part of bar 111 within the limits of guide aperture 228, the purpose of which will be described hereinbelow.

The forward end of bar 111 has an axial aperture 255 into which is secured, by press fit or otherwise, shaft 256 of substantially cone shaped socket 257. See Fig. 3. Socket 257 accommodates ball 258 secured therein by cap 259 threadably engaging the outer periphery of said socket. Mounted fast in ball 258 and extending forwardly through central aperture of cap 259 is shaft 261 of chuck body 262 having a tapered internal aperture which accommodates a plurality of removable chuck jaws 263 arrayed annularly within said chuck.

A knurled compression ring 264 threadably engages the outer periphery of chuck body 262, the annular shoulder 265 of said ring being adapted to urge jaws 263 further into the aperture of chuck body 262 when ring 264 is tightened thereon. This action reduces the space between the gripping faces of jaws 263 which thereby tighten their grip upon specimen block 266. Specimen 267 is embedded in block 266 by means well known in the art.

By virtue of the jaw structure within chuck 262, the aperture size is adjustable, thereby ensuring a firm positive grip on the specimen block along its entire length. The ball and socket means for attaching the chuck 262 to bar 111 permits angular adjustment of the specimen 267 to provide its proper orientation relative to the cutting knife. The ball and socket means provides for angular as well as radial adjustment of the specimen.

The knife holding assembly and stage therefor are located at the front portion of the machine and are positioned on horizontal platform 271 which is movable back and forth upon rails 41 and 42 of base 31. See Figs. 2 and 3. Each of the inner vertical walls of rails 41 and 42 has a longitudinal horizontal channel 272 and 273, respectively, positioned opposite each other and within which anchor plate 274 is movable longitudinally. See

Figs. 8 and 10. Extending through plate 274 is vertical lock rod 275, the upper end of which is inserted into aperture 276 in substantially the center of the bottom surface of platform 271. Aperture 276 is sufficiently deep to permit vertical movement of rod 275 therein. The lower end of rod 275 is threadably engaged by nut 277, while spring 278, coiled around rod 275, urges plate 274 downward from platform 271, the width of channels 272 and 273 being great enough to permit a slight vertical movement on the part of plate 274.

Aperture 276 is intersected at right angles by horizontal aperture 279 bored through the side of platform 271 and accommodating lever spindle 281 therein. The outer end of spindle 281 has a handle 282 for manual rotation thereof. Spindle 281 is keyed into position in platform 271 to prevent longitudinal movement by means of vertical set screw 283 threadably inserted through the top of the platform, the lower end of said screw engaging annular keyway 284 recessed in the periphery of spindle 281.

The inner end of spindle 281 is reduced somewhat in diameter and has the form of a circular cam 285, whose axis is displaced from the axis of spindle 281, thereby providing an eccentric which is inserted into cooperating circular aperture 286 in vertical rod 275.

Platform 271 may be adjustably moved along rails 41 and 42, anchor plate 274 moving therewith in channels 272 and 273 until the desired position is determined, after which handle 282 is operated to rotate lever spindle 281 causing eccentric cam 285 to force rod 275 upwards, thereby urging platform 271 downward against the top surfaces of rails 41 and 42 until a locking condition occurs between platform 271 and base 31.

By rotating handle 282 in the opposite direction, the platform is released from the locked position, this action being assisted by spring 278, and the platform can then be relocated in another position on rails 41 and 42 to be locked again in another desired position.

Positioned on the top surface of platform 271 is knife holder stage 291 having a smooth bottom surface movable freely upon the top surface of platform 271. See Figs. 2, 3, 8 and 9. The top of platform 271 has a recessed longitudinal keyway 292 which accommodates key 293 of vertical lock rod 294 which extends upward into and is movable vertically in aperture 295 in the central portion of stage 271. A captive spring 296 is positioned within aperture 295 above rod 294 and normally urges said rod downward. Key 293 has a pair of outwardly extending flanges 297 which are limited in their upward movement by shoulders 298 of keyway 292 thereby limiting the upward movement of lock rod 294. The vertical dimension of keyway 292 is sufficient to permit a slight vertical movement on the part of rod 294.

Aperture 295 is intersected at right angles by horizontal aperture 301 bored through the side of stage 291 and accommodating therein lever spindle 302. The outer end of spindle 302 has a handle 303 for manual rotation thereof. Spindle 302 is keyed into position in stage 291 to prevent longitudinal movement by means of vertical set screw 304 threadably inserted through the bottom of stage 291, the upper end of said screw engaging annular keyway 305 recessed in the periphery of spindle 302.

The inner end of spindle 302 is reduced somewhat in diameter and has the form of a circular cam 306 whose axis is displaced from the axis of spindle 302, thereby providing an eccentric which is inserted horizontally into cooperating circular aperture 307 in lock rod 294. Upon rotation of spindle 302, eccentric cam 306 causes the upward movement of lock rod 294, forcing flanges 297 upward against shoulders 298, thereby urging stage 291 downward upon platform 271 until they are locked together. Upon rotating lever 302 in the opposite direction, lock rod 294 is lowered, this action being assisted by spring 296, thereby releasing the grip between stage 291

11

and platform 271 and permitting movement of the stage horizontally relative to the platform.

Platform 271 has a rearward extension 311 (Figs. 2 and 3) at the rear end of which is mounted upwardly extending bracket 312 whose upper portion is substantially coextensive with the base portion of stage 291. Bracket 312 has a pair of recesses 313 in the front face thereof which accommodate the respective ends of a pair of springs 314 which extend forwardly into corresponding horizontal apertures 315 in stage 291. Springs 314 normally urge stage 291 forward from bracket 312.

Mounted on the front end of platform 271 is a pair of brackets 316 between which is mounted pin 317 which pivotally supports adjustment bar 318. A short portion of bar 318 extends upward from pin 317 and the larger portion of said bar extends downward below said pin. Threadably inserted through the lower end of bar 318 is thumb screw 319 having a knurled head, the inner end of said screw bearing against downwardly extending bracket 321 connected to platform 271. Threadably inserted through the upper end of bar 318 is a thumb screw 322 having a knurled head, the inner end of said screw bearing against the forward vertical face of stage 291. Screw 322 serves as a coarse adjustment for the stage 291 relative to platform 271, while screw 319 serves as a fine adjustment means for the stage relative to the platform.

After platform 271 has been locked in position relative to base 31, it is necessary to adjust the knife to a position which is critical relative to the specimen. Hence, lever 303 of spindle 302 is rotated in a manner to permit free movement of stage 291 relative to platform 271, subject only to the action of springs 314 for a coarse adjustment. Screw 322 is rotated until an approximated position of coarse adjustment is reached, after which screw 319 is rotated to provide a fine adjustment to the precise position that is desirable for the knife, at which point lever 302 is rotated to lock stage 291 to platform 271, as described hereinabove.

The casting of stage 291 has an upwardly extending boss 325 that terminates in a split collar 326 whose longitudinal mouth 327 is formed by upper lip 328 and lower lip 329. See Figs. 2, 3 and 8. Positioned in vertical coaxial apertures in lips 328 and 329 and movable vertically therein is grip bolt 331, the lower end of said bolt bearing against the upper end of captive spring 332 in aperture 333 of lower lip 329 and which normally urges bolt 331 upwards.

Aperture 333 is intersected at right angles by horizontal aperture 335 in lower lip 329 which accommodates lever spindle 336, to the outer end of which is attached operating handle 337. Fig. 2. The inner end of spindle 336 is reduced in diameter and has the form of a circular cam whose axis is displaced from the axis of spindle 336, thereby providing an eccentric which is inserted horizontally into mating aperture 338 in bolt 331 (Fig. 3).

Inserted horizontally in collar 326 is a cylindrical sleeve 340, having a longitudinal slot 341 (Fig. 11), and which is locked into position therein by turning spindle 336, causing bolt 331 to move downward to constrict mouth 327 thereby reducing the diameter of said collar which now grips the sleeve tightly. When lever 336 is rotated in the opposite direction, bolt 331 is moved upward assisted by the action of spring 332 whereby collar 326 is loosened to release sleeve 340.

While sleeve 340 is movable longitudinally within collar 326, the rotation of the sleeve relative to the collar is prevented by key 342 (Fig. 3) extending longitudinally upon the outer periphery of the sleeve and riding in longitudinal mating keyway 343 in the inner periphery of the collar. Although key 342 and keyway 343 are shown in Fig. 3 as being intermediate the top and bottom of sleeve 340 and collar 326, respectively, the illustration in Fig. 8 shows the key and keyway at the top of the collar and sleeve respectively, in order more clearly to

12

illustrate the action thereof. Of course, the key and keyway may be arranged in any other suitable position.

Longitudinally inserted into sleeve 340 and fitting smoothly therewith is block 344 (Figs. 3, 8 and 11) secured into said sleeve by means of pressure plate 345 enclosing the outer end of the sleeve. Pressure plate 345 has an aperture 346 through which shoulder screw 347 extends and threadably engages aperture 348 in said block. Screw 347, which has a knurled head 349 for manual operation, causes a tight locking action between block 344, on the one hand, and pressure plate 345 and sleeve 340, on the other hand, the pressure plate being provided with an annular cam 351 which bears against a mating annulus 352 on one end of sleeve 340. The other end of sleeve 340 has an angular edge 353 which mates with and bears against an annular recess 354 on a flanged annular extension 355 on block 344. By loosening screw 347, block 344 may be adjustably rotated within sleeve 340 and subsequently locked therein in any desired position.

The internal diameter of sleeve 340 is slightly greater than the outside diameter of block 344 whereby the latter is freely movable longitudinally and radially within the former. When the assembly of block 344 and sleeve 340 are locked in position in collar 326, slot 341 permits the internal diameter of sleeve 340 to be reduced thereby assuring that the gripping action of collar 326 will be transmitted through split sleeve 340 to block 344.

Flange 355 has a pair of extensions 356 and 357, respectively, which together form a holder for knife 358. Bottom extension 357 has a pair of studs 361 which serve as a support for one or two edges of the knife, while upper extension 356 has an obliquely downwardly extending threaded aperture 362 accommodating screw 363 having a knurled head 364 for manual operation, the end 365 of said screw being adapted to bear upon another edge of the knife. (Fig. 12). Studs 361 and the end 365 of screw 363 serve as a three point foundation for a knife which may be formed of a broken piece of glass.

Knife 358 may be cut from window glass or the like, having a suitable thickness, such as $\frac{3}{16}$ inch, for example, substantially in the shape of a rhomboidal equilateral parallelogram with the cutting edge 366 having an acute angle, such as 45° , for example. It is evident, however, that in cutting a piece of glass, its contour may be somewhat irregular and, therefore, the provision of a three-point mounting—studs 361, screw point 365—permits firm support and wide latitude of adjustment for the knife to bring its cutting edge to its optimum cutting position.

In order to provide additional rigidity to the mounting of knife 358, there is provided pressure plate 371 which is movable laterally between extensions 356 and 357 toward the outside vertical face of said knife, and which bears against it and urges its opposite vertical face against the end of block 344. Plate 371 has a central aperture which accommodates shoulder screw 373 which rotates freely therein, the head of the screw being recessed below the clamping surface of the plate.

Pressure plate 371 is mounted on the inner end of stud screw 374 having a central longitudinal aperture 375 threadably engaged by screw 373. Stud screw 374, having a knurled head 376 for manual operation, is threadably inserted into end plate 377 which in turn is secured to extensions 356 and 357 by means of screws 378. Thus, the rotation of screw 374 in stationary end plate 377 will cause pressure plate 371 to move laterally between extensions 356 and 357, whereby knife 358 may be released from, or tightened into, the knife holder. The provision of lateral adjustment of pressure plate 371 permits the knife holder to accommodate itself to knives of different thicknesses. It is understood, of course, that knife 358 may be made of suitable steel materials other than the glass knife that has been described.

Once knife 358 is tightened into its mounting in knife block 344, and while screw 347 is loose, the block is

rotated within sleeve 340 until the cutting edge 366 is in its optimum position, after which screw 347 is tightened to secure block 344 fast in sleeve 340. Thereafter, while lever spindle 336 has been rotated to loosen collar 326, sleeve 340 containing the knife mounting assembly may be moved laterally in respect of specimen 267 to the optimum cutting position, after which lever spindle 336 is rotated in the opposite direction and collar 326 tightened around sleeve 340, thereby locking the knife holder assembly in position.

First, the cutting edge of the knife is sighted horizontally relative to the specimen while rotating block 344 within sleeve 340; and when the knife is aligned horizontally with the specimen, the block is locked in position within the sleeve by tightening screw 347. During this first operation sleeve 340 is prevented from rotating by reason of the engagement of key 342 with keyway 343 in collar 326. Next, the operator sights the knife vertically while moving the assembly of sleeve 340 and block 344 laterally within collar 326 until the knife and the specimen are in vertical alignment at which point the knife assembly is locked in collar 326 by rotating spindle lever 336 by means of handle 337.

In operation, specimen block 266, in which specimen 267 is embedded, is mounted in chuck 262 of the specimen holder. Ball 258 is adjusted in socket 257, either radially, or angularly, or both, in respect of bar 111 to provide the optimum position for the specimen relative to cutting edge 366 of knife 358. Platform 271 is secured in position by manipulating handle 282 of lever 284, and the position of stage 291 relative to platform 271 is adjusted by means of the coarse and fine adjustment screws 322 and 319, respectively, after which handle 303 of lever 302 is manipulated to lock the stage to the platform. The cutting angle and the position of cutting knife 358 is adjusted by horizontal and vertical sighting of cutting edge 366 relative to specimen 267 as described hereinabove.

Specimen 267 is then oscillated past cutting edge 366 of knife 358 by the operator grasping handle 232 and rotating wheel 231, thereby causing the crank and linkage connection between said wheel and bar 111 to move the latter in a path determined by the contours of aperture 288 in guide plate 225.

Referring to Fig. 13, specimen advancing bar 111 is shown in the process of moving downward in a vertical path whereby the specimen is moved past and against the cutting edge of the knife. After a slice of tissue has been cut from the specimen, cutting bar moves downward diagonally toward the left, after which it moves upward in a second vertical path thereby causing the specimen to bypass the cutting knife. A second diagonal cam edge of aperture 228 causes bar 111 to move upward to the right to a starting position, after which the cutting cycle is repeated.

In order to ensure a straight line motion in the vertical track bar 111 in passing the specimen across knife 358, a starting recess A is provided at the top of aperture 228, which is offset to the right from vertical edge B of said aperture. When bar 111 is caused to move downward by the crank linkage, described hereinabove, bar 111 moves slightly toward the left as it emerges from recess A, and moves downward along edge B against which it is biased by the residual friction engendered between balls 104 and 105 upon pivot rod 101, said balls being spring biased upon the ends of said rod by spring blades 106 and 107 mounted on pivot block 91. See Fig. 5.

After the slicing action has taken place, bar 111 moves diagonally downward to the left along edge C of aperture 228 until it reaches recess D which is slightly offset from vertical return edge E. The relationship of recess D to edge E provides for the same biasing action as recess A performs for the bar in respect of its transit along edge B. The return path of bar 111 is defined by aperture edge E whereby the specimen bypasses the knife at a safe dis-

tance, after which cutting bar 111 is returned along the upwardly extending diagonal edge G of aperture 228 to its original position in recess A.

It will be remembered that the linkage between crank 5 disc 235 and bar 111 is loosely articulated at its upper and lower ends. See Fig. 13 and description above. This was provided in order to permit bar 111 to rotate pivotally within guide plate 225 whose plane is substantially perpendicular to the plane of rotation of crank pin 242. 10 In order to take up the slack that such a linkage entails, the downward pull of spring 113 (Fig. 4) continually urges the forward end of bar 111 upwards, thereby obviating any play that might otherwise exist between pin 242 and link 243, and between link 245 and pin 246, respectively.

In previous microtomes, static friction engendered by the motion of the specimen holder and its whole assembly has introduced aberrations into the advancing mechanism which has caused undesirable variations in the tissue slicing operation. In the microtome of the present invention, however, static friction has been reduced, if not eliminated entirely, by having the bar 111, moving principally only at its forward end, describe a virtually circular motion, thus avoiding the complete stop and reversal 20 actions that are characteristic of other instruments. At the same time this circular motion of bar 111, and, accordingly, of the specimen holder enables the tissue specimen to bypass the knife edge on the return stroke, thus eliminating possible damage to the tissue block and 25 the specimen embedded therein.

The apparatus of the present invention provides this bypass action by means of the novel pivot action whereby the specimen on the forward end of bar 111 is moved in a virtual circular plane while the rear end of the bar is 30 based in a bearing ball pivoting assembly which ensures dimensional stability without sacrificing any degree of accuracy and of flexibility of operation.

The specimen is advanced toward the cutting knife in 35 minute increments whereby extremely thin tissues are cut. 40 Each 360° turn of wheel 231 moves bar 111 through one complete cutting cycle by means of the connecting rod linkage near the forward end of the bar.

Lever arm 171 moves with bar 111 and lifts rod 175, 45 on each upward stroke, thereby causing ratchet wheel 188 to rotate a predetermined radial distance, depending upon the pre-selection made on knob 211, as described hereinabove. Upon rotation of ratchet wheel 188, screw 120 is likewise rotated the same distance to cause the specimen to advance toward the cutting knife. It will be observed that during this advancing action, the specimen is in its upward transit with bar 111 riding along edge E of aperture 228 in guide plate 225, and at that time the specimen is bypassing the knife. When bar 111 moves downward along edge B of the guide plate, the 50 specimen is being cut and at that time pawl 186 moves downward and is disengaged from teeth 187 of wheel 188. As indicated hereinabove, the incorporation of spring 201 for lifting pawl 186 away from teeth 187 is desirable to prevent the pawl from bouncing or chattering on said teeth in its return stroke so as to eliminate 55 any vibrations that might otherwise be imparted to the specimen.

In one typical embodiment, ratchet wheel 188 has 100 teeth 187, while threads 121 of screw 120 have a thread pitch of 0.5 mm. Therefore, one complete revolution of ratchet wheel 188 advances block 144 a distance of 0.5 mm. If cam disc 192 were arranged to permit pawl 186 to engage teeth 187 of wheel 188 at such a position whereby said wheel would be advanced the radial space of only one tooth, then rider block 144 would advance only 0.005 mm.

Referring to the compound pivot mounting of cutting bar 111, the common horizontal axis of balls 65 and 76 is spaced apart vertically from the common horizontal axis of balls 95 and 96, as is schematically illustrated in

15

Fig. 5A. In the embodiment referred to, these two horizontal axes are spaced apart by 0.025". If the overall length between pivot point 139 of yoke 80 and leg 87 and the pivot mounting on balls 65 and 76 is 5", and the transmitted force is applied to balls 95 and 96, which serve as the pivot point for bar 111 and which are offset from balls 65 and 76 by 0.025", it can be seen that a reduction ratio of 200:1 is obtained.

Assuming that ratchet wheel 188 is advanced radially by a distance of one tooth on the periphery of said wheel, and rider block advances 0.005 mm., since the forward motion of bar 111 is only $\frac{1}{200}$ of the motion of rider block 144, as illustrated schematically in Fig. 5B (where for purposes of clarity of illustration, the block actually has been displaced by a greater number of turns on screw 120), the specimen, attached to the forward end of bar 111, advances toward knife edge 366 by $\frac{1}{200}$ of 0.005 mm., or 0.000025 mm., which is equivalent to 0.025 micron, or $\frac{1}{40}$ micron.

It is apparent that the thickness of tissues to be cut in multiples of a micron may be predetermined by manipulating knob 211 to rotate cam disc 192 thereby permitting pawl 186 to engage peripheral teeth 187 of ratchet wheel 188 at distances indicated on the calibrated scale 212 on knob 211 in order to provide a greater amount of rotation on screw 120 to cause bar 111 to advance the proportionately greater distance toward the cutting knife.

Although the axis of the pivot mounting for bar 111 of balls 95 and 96 has been described as being slightly below the axis of the pivot mounting of yoke 80 on balls 65 and 76, it will be understood that the positions of these respective axes may be reversed in some embodiments provided the direction of the screw threads 121 is reversed on screw 120 with a corresponding reversal of the other cooperating parts. In either case, the combination of yoke 80 and leg 87, acting as a lever, provide the means for advancing the specimen to the cutting knife.

In the specification, I have explained the principles of my invention, and the best mode in which I have contemplated applying those principles, so as to distinguish my invention from other inventions; and I have particularly pointed out and distinctly claimed the part, mode or combination which I claim as my invention or discovery.

While I have shown and described certain preferred embodiments of my invention, it will be understood that modifications and changes may be made without departing from the function and scope thereof, as will be clear to those skilled in the art.

I claim:

1. A microtome comprising a base, a cutting knife mounted on said base, a first frame mounted on said base, a second frame mounted on said first frame and pivotable vertically relative thereto, advancing means mounted on said second frame and pivotable horizontally relative thereto, and a specimen mounted on the outer end of said advancing means extending towards said knife, said advancing means and said specimen being movable in all lateral directions relative to said knife.

2. A microtome comprising a base, a cutting knife mounted on said base, a support means mounted on said base, a frame, a first pivot mounting connecting said frame to said support means for pivoting motion in one direction, specimen advancing means, a second pivot mounting connecting one end of said advancing means to said frame for pivoting motion in a 90° direction relative to the first pivoting motion, both of said pivot mountings together forming a compound pivot mounting for said advancing means whereby the other end of said advancing means may be moved laterally in all directions.

3. A microtome comprising a base, a cutting knife mounted on said base, a support means mounted on said base, a frame, a first pivot mounting connecting said frame to said support means for pivoting motion in one direction, specimen advancing means, a second pivot

16

mounting connecting said advancing means to said frame for pivoting motion in a 90° direction relative to the first pivoting motion, both of said pivot mountings together forming a compound pivot mounting for said advancing means whereby the outer end of said advancing means may be moved laterally in all directions, each of said first and second pivot mountings comprising a pair of balls, and spring loading means in which said balls are seated.

4. A microtome comprising a base, a knife mounted on said base, a support means mounted on said base, a lever pivotally connected to said support means, a frame, a first pivot mounting connecting said frame to said lever for pivoting motion in one direction, specimen advancing means adapted to hold a specimen on its outer end, a second pivot mounting connecting said advancing means to said frame for pivoting motion in a 90° direction relative to the first mentioned pivoting motion, both of said pivot mountings together forming a compound pivot mounting for said advancing means whereby the outer end of said means may be moved laterally in all directions, the first pivot mounting being slightly spaced apart from the fulcrum of said lever whereby the movement of the latter causes the outer end of said advancing means to move toward said knife.

5. A microtome comprising a base, a knife mounted on said base, a support means mounted on said base, a lever pivotally connected to said support means, a frame, a first pivot mounting connecting said frame to said lever for pivoting motion in one direction, advancing means adapted to hold a specimen on its outer end, and a second pivot mounting connecting said advancing means to said frame for pivoting motion in a 90° direction relative to the first mentioned pivoting motion, both of said pivot mountings together forming a compound pivot mounting for said advancing means whereby the outer end of said means may be moved laterally in all directions, the first pivot mounting being spaced apart from the fulcrum of said lever whereby the movement of the latter causes the outer end of said advancing means to move toward said knife, each of said first and second pivot mountings comprising a pair of balls.

6. A microtome comprising a base, a knife mounted on said base, a support means mounted on said base, a lever pivotally connected to said support means, a frame, a first pivot mounting connecting said frame to said lever for pivoting motion in one direction, advancing means adapted to hold a specimen on its outer end, a second pivot mounting connecting said advancing means to said frame for pivoting motion in a 90° direction relative to the first mentioned pivoting motion, both of said pivot mountings together forming a compound pivot mounting for said advancing means whereby the outer end of said means may be moved laterally in all directions, the first pivot mounting being spaced apart from the fulcrum of said lever whereby the movement of the latter causes the outer end of said advancing means to move toward said knife, each of said first and second pivot mountings comprising a pair of balls, and spring loading means in which said balls are seated.

7. A microtome comprising a base, a knife mounted on said base, a support means mounted on said base, a lever, one end of said lever being in the form of a yoke, the yoke portion of said lever being pivotally connected to said support means, a frame, a first pivot mounting connecting said frame between the arms of said yoke for pivoting motion in one direction, advancing means adapted to accommodate a specimen on one of its ends, a second pivot mounting connecting the other end of said advancing means to said frame for pivoting motion in a 90° direction relative to the first mentioned pivoting motion, both of said pivot mountings together forming a compound pivot mounting for said advancing means whereby the specimen end of said means may be moved laterally in all directions, the first pivot mounting being spaced apart from the fulcrum of said lever whereby the

movement of the latter causes the specimen end of said advancing means to move toward said knife.

8. A microtome comprising a base, a knife mounted on said base, a support means mounted on said base, a lever, one end of said lever being in the form of a yoke, the yoke portion of said lever being pivotally connected to said support means, a frame, a first pivot mounting connecting said frame between the arms of said yoke for pivoting motion in one direction, advancing means adapted to accommodate a specimen on one of its ends, and a second pivot mounting connecting the other end of said advancing means to said frame for pivoting motion in a 90° direction relative to the first mentioned pivoting motion, both of said pivot mountings together forming a compound pivot mounting for said advancing means whereby the specimen end of said means may be moved laterally in all directions, the first pivot mounting being spaced apart from the fulcrum of said lever whereby the movement of the latter causes the specimen end of said advancing means to move toward said knife, the pivotal connection of the lever to the support means and the first and second pivot mountings each comprising a pair of balls.

9. A microtome comprising a base, a knife mounted on said base, a support means mounted on said base, a lever, one end of said lever being in the form of a yoke, the yoke portion of said lever being pivotally connected to said support means, a frame, a first pivot mounting connecting said frame between the arms of said yoke for pivoting motion in one direction, advancing means adapted to accommodate a specimen on one of its ends, a second pivot mounting connecting the other end of said advancing means to said frame for pivoting motion in a 90° direction relative to the first mentioned pivoting motion, both of said pivot mountings together forming a compound pivot mounting for said advancing means whereby the specimen end of said means may be moved laterally in all directions, the first pivot mounting being spaced apart from the fulcrum of said lever whereby the movement of the latter causes the specimen end of said advancing means to move toward said knife, the pivotal connection of the lever to the support means and the first and second pivot mountings each comprising a pair of balls.

10. A microtome comprising a base, a knife mounted on said base, a support means mounted on said base, a specimen holder adapted to accommodate a specimen on its outer end, a compound pivoting connection on the other end of said specimen holder connecting the latter of said support means whereby said specimen may be moved in all lateral directions relative to said knife, a guide plate mounted on said base, an aperture in said plate through which the outer end of said specimen holder extends, the contours of said guide plate causing said specimen holder to carry said specimen past said knife in one direction only and to bypass the specimen around said knife during the remainder of the motion of said specimen holder.

11. A microtome comprising a base, a knife mounted on said base, a support means mounted on said base, a specimen holder adapted to accommodate a specimen on its outer end, a compound pivoting connection on the other end of said specimen holder connecting the latter to said support means whereby said specimen may be moved in all lateral directions relative to said knife, a guide plate mounted on said base, an aperture in said plate through which the outer end of said specimen holder extends, the contours of said guide plate causing said specimen holder to carry said specimen past said knife in one direction only and to bypass the specimen around said knife during the remainder of the motion of said specimen holder, means for moving said compound pivoting connection towards said knife, and means for moving said specimen holder in cycles within said aperture.

12. A microtome comprising a base, a knife mounted on said base, a support means mounted on said base, a specimen holder adapted to accommodate a specimen on its outer end, a plurality of spring loaded balls forming a compound pivot mounting on the other end of said specimen holder connecting the latter to said support means whereby said specimen may be moved in all lateral directions relative to said knife, a guide plate mounted on said base, an aperture in said plate through which the outer end of said specimen holder extends, the contours of said guide plate causing said specimen holder to carry said specimen past said knife in one direction only and to bypass the specimen around said knife during the remainder of the motion of said specimen holder, means for moving said compound pivot mounting towards said knife, means for moving said specimen holder in cycles within said aperture, said spring loaded pivot mounting being adapted to provide a biasing action to urge said holder toward the edges of said aperture.

13. A microtome comprising a base, support means mounted on said base, a lever pivotally connected to said support means, a frame, a first pivot mounting connecting said frame to said lever for pivoting motion in one direction, advancing means adapted to accommodate a specimen on one of its ends, a second pivot mounting connecting the other end of said advancing means to said frame for pivoting motion in a 90° direction relative to the first mentioned pivoting motion, both of said pivot mountings together forming a compound pivot mounting for said advancing means whereby the specimen end of said means may be moved laterally in all directions, the first pivot mounting being spaced apart from the fulcrum of said lever whereby the movement of the latter causes the specimen end of the advancing means to move toward said knife, a cutting knife, a screw mounted longitudinally relative to said advancing means in said base, thread means on said screw and on the thrust end of said lever interengaging to cause said lever to move in accordance with the rotation of said screw.

14. A microtome according to claim 13 wherein said interengaging screw thread means comprises buttress threads, and further comprising spring means connected between said lever and said support means whereby said thread interengaging means are urged together to obviate backlash and lost motion.

15. A microtome according to claim 14, and further comprising means for disengaging said interengaging thread means.

16. A microtome according to claim 14, and further comprising a pair of balls, in which the respective ends of said screw are mounted for rotation, and resilient means mounted on said base to provide a spring loading for said balls.

17. A microtome comprising a support, a lever, a first pivot mounting connecting one end of said lever to said support, specimen advancing means, a second pivot mounting connecting one end of said advancing means to said lever near said first pivot mounting, means for holding a specimen on the freely movable portion of said advancing means, means for moving the other end of said lever in predetermined increments of distance whereby the motion of the specimen advancing means is a fraction of the motion of said other end of the lever.

18. A microtome according to claim 17, and further comprising means for oscillating the free end of said advancing means relative to a cutting knife whereby a specimen is passed across said knife during one portion of said oscillation and bypasses the knife laterally during another portion of said oscillation.

19. A microtome according to claim 18, and further comprising means oscillating with said oscillating means and operative to cause the movement of said lever only during the portion of oscillation of said advancing means when the specimen bypasses the knife.

20. A microtome comprising a knife, a specimen hold-

er, a lever to which said holder is pivotally connected, said lever being adapted to move said specimen holder toward the knife, a screw mounted substantially parallel to said specimen holder, a yoke mounted pivotally on the thrust end of said lever, a rider block mounted on another portion of said yoke, threads on said block adapted to mesh with the threads on said screw, spring means bearing upon said yoke to urge said block into engagement with said screw, and means adapted to disengage said block from said screw against the action of said spring means.

21. A microtome comprising a knife, a specimen holder, a lever to which said holder is connected, said lever being adapted to move said specimen holder toward the knife, a screw mounted substantially parallel to said specimen holder, means pivotally connected to said lever for engaging the threads of said screw whereby the rotation of said screw causes said lever to move, means adapted to oscillate the specimen holder laterally relative to the cutting knife, a ratchet wheel mounted fast on said screw, and means oscillating synchronously with the lateral movement of the specimen holder and adapted to engage said ratchet wheel and move the latter within a predetermined distance.

22. A microtome comprising a knife, a specimen holder, a lever to which said holder is connected, said lever being adapted to move said specimen holder toward the knife, a screw mounted substantially parallel to said specimen holder, means pivotally connected to said lever for engaging the threads of said screw whereby the rotation of said screw causes said lever to move, means adapted to oscillate the specimen holder laterally relative to said knife, a ratchet wheel mounted fast on said screw, means oscillating synchronously with the lateral movement of the specimen holder and adapted to engage said ratchet wheel and move the latter within a predetermined distance, and means for adjusting the position at which oscillating means engages said ratchet wheel whereby the degree of rotation of said screw is controlled.

23. A microtome according to claim 22, and further comprising a pawl connected to said oscillating means and adapted to engage the teeth on said ratchet wheel during one movement of said oscillating means and to disengage from the teeth of said ratchet wheel during the return movement of said oscillating means.

24. A microtome comprising a knife, a specimen holder, a lever to which said holder is connected, said lever being adapted to move said specimen holder toward the knife, a screw mounted substantially parallel to said specimen holder, means pivotally connected to said lever for engaging the threads of said screw whereby the rotation of said screw causes said lever to move, means adapted to oscillate the specimen holder laterally in all directions relative to said knife whereby the specimen is passed across the cutting edge of the knife during one portion of its motion and bypasses the cutting knife during another portion of its motion, a ratchet wheel mounted fast on said screw, means oscillating synchronously with the movement of the specimen holder, a pawl on said synchronous oscillating means adapted to engage said ratchet wheel, means connected to said pawl for determining the distance within which said pawl engages said ratchet wheel whereby the degree of rotation of said screw is controlled, and means connected to said pawl for disengaging said pawl from said ratchet wheel during a portion of the motion of said synchronous oscillating means, said pawl being arranged to engage said ratchet wheel only when the specimen bypasses the knife.

25. A microtome according to claim 24 wherein said means for determining the distance within which the pawl engages the ratchet wheel comprises a cam disc, a cam surface on said disc, a second pawl connected to said first mentioned pawl and adapted to engage said cam

disc whereby said first pawl is caused to engage and disengage said ratchet wheel.

26. A microtome according to claim 25, and further comprising means for rotating said cam disc thereby controlling the distance during which said first pawl engages said ratchet wheel.

27. A microtome according to claim 26, and further comprising a spring connected to both of said pawls, a friction disc mounted coaxially relative to said cam disc, said spring being engaged frictionally between both of said discs whereby during a portion of the movement of said synchronous oscillating means the first mentioned pawl is caused to disengage promptly from the teeth of the ratchet wheel.

28. In a microtome, a mechanism for advancing the specimen toward the knife comprising a lever, a pivot mounting for said lever near one end thereof, a specimen holder connected pivotally to said lever, the pivotal connection between said specimen holder and said lever being slightly displaced from the first mentioned pivot mounting, and a screw engaged by the other end of said lever, the rotation of said screw causing the specimen holder to be advanced.

29. A mechanism according to claim 28 wherein said pivot mounting and pivotal connection each comprise a pair of balls.

30. A mechanism according to claim 29, and further comprising a spring loading for each of said pairs of balls.

31. In a microtome, a mechanism for advancing the specimen toward the knife comprising a lever, a pivot mounting for said lever near one end thereof, a frame pivotally connected to said lever for movement in one direction, the pivotal connection between said frame and said lever being slightly displaced from the first mentioned pivot mounting, a specimen holder pivotally connected to said frame for movement in a direction 90° relative to the movement of said frame, and a screw engaged by the other end of said lever, the rotation of said screw causing the specimen holder to be advanced, the combined pivot mountings of said frame and said specimen holder permitting the free end of said specimen holder to be moved substantially in any desired lateral direction.

32. A mechanism according to claim 31 wherein each of said pivotal mountings comprises a pair of balls.

33. A mechanism according to claim 32, and further comprising a spring loading for each of said pairs of balls.

34. A microtome comprising a knife, a specimen holder, a lever, said specimen holder being pivotally connected near one end to said lever whereby its other end may be moved laterally in any desired direction, a specimen on said other end of the specimen holder, a screw mounted substantially parallel to said specimen holder, means on said lever for engaging the threads of said screw to cause the specimen holder to move the specimen toward the knife, means adapted to oscillate the free end of said holder laterally relative to the cutting knife, a guide plate, and a guide aperture in said plate through which the specimen end of said holder extends, the contours of said guide plate being arranged to cause the specimen to pass in one direction only across the cutting edge of the knife and to bypass the knife in the remainder of its movement.

35. A microtome according to claim 34 wherein the means adapted to oscillate the free end of said holder comprises a crank, a loosely articulated link connected between said crank and said holder near said specimen and spring means mounted on said holder for taking up the slack in said link.

36. A microtome according to claim 34, and further comprising spring loading upon the pivotal connection of the specimen holder to said lever whereby said holder

is caused to be urged against the edges of said guide aperture.

37. A microtome comprising a knife, a specimen holder assembly, means for moving said assembly toward said knife, a chuck for gripping the specimen, and a ball and socket joint by which said chuck is connected to said assembly whereby the specimen may be adjusted in position rotatably or angularly in respect of the cutting edge of the knife.

38. A microtome comprising a knife, a chuck adapted 10 to hold a specimen to be cut by the knife, a holder in the form of a bar, one end of said bar having a pivot mounting whereby the other free end of said bar is movable laterally in any desired direction in respect of the knife, and a ball and socket joint by which said chuck is connected to the free end of said bar whereby the specimen may be adjusted in position rotatably or angularly 15 in respect of the cutting edge of the knife.

39. A microtome according to claim 38, and further comprising means for rotating the free end of said bar to cause the specimen to pass across the cutting edge of the knife during one portion of its motion and to bypass the cutting edge of the knife during another portion of its motion, and means for moving said bar toward said knife in predetermined increments only when the specimen is bypassing the knife.
